(57) **CLAIM**

The ornamental design for a device for monitoring of energy consumption usage as shown and described.

DESCRIPTION

FIG. 1 is a perspective view of a device for monitoring of energy consumption usage taken from a front side;

FIG. 2 is a perspective view of the device for monitoring of energy consumption usage taken from a rear side;

FIG. 3 is a front view of the device for monitoring of energy consumption usage;

FIG. 4 is a rear view of the device for monitoring of energy consumption usage;

FIG. 5 is a top view of the device for monitoring of energy consumption usage;

FIG. 6 is a bottom view of the device for monitoring of energy consumption usage;

FIG. 7 is a left side view of the device for monitoring of energy consumption usage; and,

FIG. 8 is a right side view of the device for monitoring of energy consumption usage.

The broken lines shown are included for the purpose of illustrating portions of the device for monitoring of energy consumption usage that form no part of the claimed design.
